UNITED STATES PATENT OFFICE.

ERNEST F. FISHER, OF ST. LOUIS, MISSOURI.

SEPARATOR.

Application filed April 6, 1925. Serial No. 21,052.

To all whom it may concern:

Be it known that I, ERNEST F. FISHER, a citizen of the United States, residing at St. Louis, in the State of Missouri, have invented certain new and useful Improvements in Separators, of which the following is a specification.

My invention has relation to improvements in separators for use in dust collecting systems, and consists in the novel features of construction more fully set forth in the specification and pointed out in the claims.

Briefly the invention consists in a tubular housing into which the dust-laden air is discharged and caused to swirl downwardly in an annular space by its own velocity together with the action of helical vanes. The dust particles are discharged from the ends 15 of the vanes, which are adjustable, and the air discharges into a central cylinder free from dust.

The principal object of the invention is the provision of adjustment at the discharge 25 end of the helical vanes to regulate the speed of discharge of the dust particles and also the size of the air discharge opening from the separator chamber. The advantage of this adjustment is that the separator efficiency can be maintained at its maximum 30 through a wide variation of material handled. Further advantages will be better apparent from a detailed description of the invention in connection with the accompanying 35 drawings, in which—

Figure 1 is a combined side elevation and vertical longitudinal section of the separator housing; Fig. 2 is a horizontal cross-section taken on the line 2—2 of Fig. 1; Fig. 3 is a 40 side elevation of the lower end of the cylinder carrying the helical vanes looking in a direction at right angles to that of Fig. 1; Fig. 4 is a bottom plan of the air receiving cylinder removed from casing; Fig. 5 is a 45 combined side elevation and vertical longitudinal section of a modified form of separator; and Fig. 6 is a horizontal cross-section taken on the line 6—6 of Fig. 5.

Referring to the drawings, 1 represents a 50 cylindrical casing with a conical discharge hopper 2 for the dust, or other waste product, and an air outlet 3 for the air after the dust has been separated therefrom. The air outlet pipe 3 adjoins the casing 1 at the top 55 and an inlet 4 for the dust-laden air is provided in the side of the casing 1 near the top

thereof. The casing 1 is provided at the inlet 4 with a tangentially disposed neck 5 to which may be connected the conduit or the collecting system (not shown). An air 60 receiving cylinder 6 is disposed within the casing 1, said cylinder being of substantially the same diameter as the outlet pipe 3, the lower end of which it engages, and said cylinder extending downwardly to the upper 65 end of the hopper 2.

There are two helical vanes 7 of one complete turn each disposed around and secured to the cylinder 6, the width of said vanes being equal to that of the space between 70 the cylinder 6 and casing 1 (except for clearance in inserting the cylinder into the casing). For the last quarter of each vane it is free from the cylinder (see Fig. 1) and said vane has formed integrally with it an 75 extension 8 extending over about one-quarter of the area of the cylinder. Hinged to this extension, at 9 is a flap 10 adapted to cover one quarter of the area of the cylinder 80 adjacent to the quarter covered by the extension 8, said flap serving as an air discharge adjustment valve. Thus the extension 8 and flap 10 of one vane cover one half of the lower end of cylinder 6, while the extension 8 and flap 10 of the other vane 85 cover the opposite half of the lower end of cylinder 6. Obviously, if both extensions 8 and both flaps 10 are held against the end of cylinder 6, the cylinder will be completely 90 closed at this end. Reversely, if the extensions 8 and flaps 10 are withdrawn from the end of the cylinder 6, then the cylinder may 95 be opened to correspond with the degree the extensions and flaps are removed therefrom. I accomplish this result by rods 11 and 12 100 secured at their lower ends to the extensions 8 and flaps 10, and passed through the cylinder and through openings in a flange 13 at the upper end of the cylinder. The rods 11, 12 are threaded at their upper ends and are 105 secured in proper adjusted position by nuts 110 n, n'.

In operation there must always be some space between extensions 8, flaps 10 and the bottom of the cylinder 6, because the air that 105 carries the dust or other material into the separator must pass into the cylinder after the dust particles have been separated out. This will be better apparent from the following description of the operation of the 110 separator. We will assume that the intake 5 has been connected to the conduit of the

collector system and the dust laden air is forced into the casing 1 by a suitable blower, as is well understood in the art.

The rapidly moving body of air will be caused by the casing to follow a circular path and at the same time will be forced downwardly by the helical vanes 7. At the same time the dust particles or other solids which are to be separated from the air will be forced outwardly by the centrifugal action. Thus, as the dust particles are concentrated near the cylindrical wall of the casing 1 they are also accelerated in their downward course by the vanes 7, until they are discharged off the end of each vane.

The moving body of air, after the heavier dust particles have been precipitated, escapes into the cylinder 6 through the spaces between the lower end of said cylinder and vane extensions 8 and flaps 10. Should the dust particles be very light they may not readily discharge from the ends of vanes 7, in which event the rods are adjusted downwardly thus lowering the discharge end of the vane and increasing the downward inclination thereof. This downward adjustment of the vane discharge end, also increases the space between the extension 8 and bottom of cylinder 6, thus enlarging the air outlet from the casing. Therefore, it may be necessary to compensate for this by adjusting rods 12 so as to close the space between flap 10 and the cylinder 6.

Thus the extensions 8 and flaps 10 may be adjusted to vary the air discharge from the casing or the inclination of the discharge end of the vane, or both of these discharges may be adjusted to suit the conditions and obtain the greatest efficiency from the separator.

In the modification shown in Figures 5 and 6, I accomplish the same object by slightly different means. Instead of two helical vanes, there are four vanes 20, each of which has a right angled extension 21 projecting over one quarter of the lower end of cylinder 6. A rod 22 is connected to the extension of each vane near the discharge end thereof, said rod being secured to the flange of cylinder 6 similarly to the rods of the main form. In adjusting the rod of any vane the air discharge space between extension 21 and the bottom of the cylinder 6, and the inclination of the discharge end of the vane are adjusted together. The operation of the modified form of separator is the same as that of the main form.

Obviously, the separator may be operated by suction applied to the air outlet 3 in lieu of plenum applied to the inlet 5. Other modifications within the purview of the skilled mechanic are also contemplated as being within the invention.

Having described my invention, I claim:

1. A separator of the character described

comprising a cylindrical casing having a tangentially disposed inlet for dust laden air, an air outlet at the top thereof, and a conical hopper at the bottom thereof, an air receiving cylinder communicating with said outlet and disposed within the casing, said cylinder having its axis coincident with that of the casing, a plurality of helical vanes between the casing and cylinder, the lower ends of said vanes being movable and being provided with suitable extensions contiguous to the lower end of the aforesaid cylinder, and means for adjusting the plane of inclination of the vane terminals and the extensions to and from the cylinder.

2. A separator of the character described comprising a cylindrical casing having a tangentially disposed inlet for dust laden air, an air outlet at the top thereof, and a conical hopper at the bottom thereof, an air receiving cylinder communicating with said outlet and disposed within the casing, said cylinder having its axis coincident with that of the casing, a plurality of helical vanes between the casing and cylinder, the lower ends of said vanes being movable and being provided with suitable extensions contiguous to the lower end of the aforesaid cylinder, means for adjusting the plane of inclination of the vane terminals, air discharge valves hingedly secured to the said extensions, and means for moving said valves to adjust the air discharge opening into the receiving cylinder.

3. A separator of the character described comprising a cylindrical casing having a tangentially disposed inlet for dust laden air, an air outlet at the top thereof, and a conical hopper at the bottom thereof, an air receiving cylinder communicating with said outlet and disposed within the casing, said cylinder having its axis coincident with that of the casing, a plurality of helical vanes between the casing and cylinder, air discharge valves adjacent to the lower end of the receiving cylinder, and means for adjusting the position of said valves to regulate the air discharge into the cylinder.

4. A separator of the character described comprising a cylindrical casing having a tangentially disposed inlet for dust laden air, an air outlet at the top thereof, and a conical hopper at the bottom thereof, an air receiving cylinder communicating with said outlet and disposed within the casing, said cylinder having its axis coincident with that of the casing, a plurality of helical vanes between the casing and cylinder, inclined discharge members for the dust adjacent to the vanes and means for adjusting the angle of inclination of said members.

In testimony whereof I hereunto affix my signature.

ERNEST F. FISHER.
